UNITED STATES PATENT OFFICE.

HENRY L. FRITZ, OF LOS ANGELES, CALIFORNIA.

MOVING-PICTURE PROJECTING APPARATUS.

1,081,733.

Specification of Letters Patent. Patented Dec. 16, 1913.

Application filed June 6, 1910. Serial No. 565,281.

To all whom it may concern:

Be it known that I, HENRY L. FRITZ, a citizen of the United States, residing at Los Angeles, in the county of Los Angeles and State of California, have invented new and useful Improvements in Moving-Picture Projecting Apparatus, of which the following is a specification.

This invention relates to a projecting apparatus for throwing pictures upon a screen, that is, such a device as is used in theaters in "moving picture" exhibits.

The object of the invention is to produce an apparatus of this class having improved means for controlling a portion of the film at a point opposite the lens so as to enable the operator to adjust the position of the image which is thrown upon the screen.

In the annexed drawing forming a part of this specification, Figure 1 is a side elevation and partial section of the apparatus, certain parts being broken away, the case of the device being shown in longitudinal section. Fig. 2 is a side elevation of a part 25 of the mechanism showing the side wall of the device removed, certain parts being broken away. Fig. 3 is a front elevation of the apparatus, certain parts being broken away. Fig. 4 is a horizontal cross section 30 taken through the rear end of the apparatus opposite the lens and illustrates the means for guiding the film.

Referring more particularly to the parts and especially in Figs. 1 and 3, 8 represents 35 the base of the apparatus upon which is mounted a bracket 9, the upper portion of which is formed into a box or case 10. The forward end of this case 10 is in the form of a block 11, having a horizontal bore 12 therein, in which the lens 13 is attached, so as to project from the case and toward the screen upon which the pictures are cast.

Within the case 10, I provide an adjusting frame 14, which is formed of two curved side arms 15, one of which is pivotally attached on a stud 16 at the left side of the apparatus, while the other is pivotally attached to a stud 17 on the opposite side. The forward ends of the arms 15 are received in pockets or recesses 18 formed in the side edges of the block 11 as indicated. The arms 15 are connected by a cross-bar 19, which is offset above the bore 12 so as not to cut off the light passing through the lens. The lower ends of the arms 15 are connected by a horizontal cross-bar or brace

19 and at the left side of the machine a link 20 is attached to the adjacent arm 15, and this link is attached to a lever 21 having pivot on the clamp bolt 22 on the bracket 60 or stand 9. From this arrangement it should, be understood that by raising or lowering the lever 21, frame 14 may be raised or lowered.

The film 23 passes down from a supply 65 reel 24, which is mounted on an elevated arm 25, which projects upwardly from a seat 26 formed on the upper side of the case and from the reel 24 it passes between guide rollers 27 and 28 disposed adjacent to the 70 upper side of the case 10 as indicated. At this point, the film passes to the rear end of the case where it is guided down through the case in a slot 29 in rear wall 30 of the case or box. As indicated in Fig. 1 at the 75 side edges of this guide slot 29, guide bars 31 are provided which extend downwardly and are formed so that the lower ends form inwardly projecting tongues 32 near the bottom wall 33 of the case. Adjacent to the 80 tongues 32, similar downwardly projecting curved tongues 34 are provided, which are attached to the inner face of the wall 30. As indicated in Fig. 1, these tongues 32 and 34 converge downwardly so as to form a 85 guide space through which the film passes. After leaving the tongues 32 and 34, the film passes between guide rollers 35 and 36, which rollers are rotatably mounted between the arms 15 of the frame 14. The roller 35 90 is clearly illustrated in Fig. 4. It has a reduced body 37 and enlarged heads 38, said heads being formed with projecting teeth 39, which are adapted to engage the perforations which are formed in the edges of the 95 film in the usual manner. The roller 36 cooperates with the heads 38 so as to keep the film in engagement with the teeth 39 as will be readily understood.

As indicated in Fig. 4, the stud 45 forms 100 a stub shaft passing out through the side wall of the case through a suitable curved slot 76. On the outer part of this shaft, a fly-wheel or balance wheel 77 is attached, which tends to cause the wheel 44 to rotate 105 at a uniform velocity. Beyond the wheel 77, a shaft 45 is provided with a pinion 78 and this pinion is driven by a master gear 79, which is rotatably mounted on the side of the case on the stud 16. In order to drive 110 the master-gear, it is provided with a rigid pinion 80 and this pinion is driven by a simi-

lar pinion 81 carried upon a cross shaft 82, which extends through the upper part of the block 11 and projects at the right side of the case where it is provided with crank 83 for 5 rotating it.

The mode of operation of the mechanism will now be described: When the crank 83 is rotated the shaft 82 imparts rotation to the pinion 80 on the hub of the master gear 79 and this master gear rotates both guide rollers 27 and 86 so as to advance the film through the case and across the light opening 52. The master gear also rotates the pinion 78 on the shaft 45 which drives the wheel 44 and the guide roller 37 which is mounted on the adjusting frame 14. By reason of the slot 76 the shaft 45 passing through the wall of the case does not prevent the adjusting frame from being elevated or lowered by means of lever 21 so as to adjust the position of the film as it passes the light opening. In this way the operator controls the position of the picture which is projected upon the screen.

What I claim is:—

An apparatus of the class described for 25 projecting pictures, a casing having a light opening therethrough, means for guiding the film through the casing, a continuous feed roller mounted on said casing, a yoke 30 frame pivotally mounted in the axial line of said casing, an interrupted feed roller mounted in said yoke frame, a pair of feed rollers mounted on said casing, gears on each 35 of said rollers, an intermediate gear on the pivot of the yoke imparting motion to each of said rollers co-operatively, a link hinged to the free end of the yoke, an adjustable operating lever connected to said link and means to clamp said lever when the picture 40 projected is framed.

In witness that I claim the foregoing I have hereunto subscribed my name this 21st day of May, 1910.

HENRY L. FRITZ.
